Catherine Mascitelli, New York, N. Y.

Application January 29, 1940, Serial No. 89,826

Term of patent 3½ years

To all whom it may concern:

Be it known that I, Catherine Mascitelli, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the back view thereof on a reduced scale.

The design is characterized by the combination on the specific dress disclosed of the blouse portion which is embroidered with elastic threads and which has self-piping around the neck, sleeves, waistline, and down the front to association with the matching bows on the sleeves and down the front, all as shown.

I claim:

The ornamental design for a dress, substantially as shown and described.
